(57) **CLAIM**

A shower door assembly, as shown and described.

DESCRIPTION

FIG. 1 is a front perspective view from the front, the top and one side of a shower door assembly according to the design, FIG. 2 is a perspective view from the rear, the top and the other side to that of FIG. 1 of the shower door assembly of FIG. 1,

FIG. 3 is a front elevational view of the shower door assembly of FIG. 1,

FIG. 4 is a rear elevational view of the shower door assembly of FIG. 1,

FIG. 5 is a side elevational view of the shower door assembly of FIG. 1,

FIG. 6 is a side elevational view of the shower door assembly of FIG. 1, from the other side to that of FIG. 5, FIG. 7 is a top plan view of the shower door assembly of FIG. 1,

FIG. 8 is a front perspective view from the front, the top and one side of a shower door assembly according to the design in a different state to that of FIG. 1,

FIG. 9 is a perspective view from the rear, the top and the same side as that of FIG. 8 of the shower door assembly of FIG. 1 in the state of FIG. 8,

FIG. 10 is a front elevational view of the shower door assembly of FIG. 1 in the state of FIG. 8,

FIG. 11 is a rear elevational view of the shower door assembly of FIG. 1 in the state of FIG. 8,

FIG. 12 is a side elevational view of the shower door assembly of FIG. 1 in the state of FIG. 8,

FIG. 13 is a side elevational view of the shower door assembly of FIG. 1 in the state of FIG. 8, from the other side to that of FIG. 12; and,

FIG. 14 is a top plan view of the shower door assembly of FIG. 1 in the state of FIG. 8.
